UNITED STATES PATENT OFFICE

CHARLES N. FAIRCHILD, OF MILFORD, CONNECTICUT, ASSIGNOR TO FAIRCHILD LOCK CORPORATION, OF NEW YORK, N. Y., A CORPORATION OF DELAWARE

TRIP LOCK

Application filed May 25, 1925. Serial No. 22,805.

This invention relates to locks in general and has for its principal object the provision of a coincidental lock, that is one in which the shutting off of the ignition is necessarily simultaneous with or subsequent to the locking of the car and in which the turning on of the ignition prior to unlocking is prevented, in which the driver is forced to withdraw the key from the lock before he can drive the automobile.

A further object of the present invention is the provision of a coincidental lock in which the usual key slot is closed by a lever which can be swung to clear the slot only when the bolt is in locking position.

A still further object of the invention is the provision of a lock of any type in which the bolt is moved to locking position against a resistance.

A still further object of the invention is the provision of a lock of any type in which the shooting of the bolt withdraws it and the locking is performed in opposition to the means which shoots the bolt to unlocking position.

Owing to the enormous percentage among stolen automobiles of those which are provided with locking devices but in which the locking devices were not in locked position at the time the theft occurred the Underwriters have created a class which they call Group I which includes those locks in which the driver of the car may not leave the car unlocked unless he also leaves the ignition on and the engine running. It is quite advantageous with these Group I locks that the owner of the car should remove the key from the lock while the automobile is in operation provided of course, that due and proper steps are taken to prevent accidental locking of the car while it is in motion. I have therefore designed the present coincidental lock in which the key can be inserted in its lock only when the locking bolt is in forward or locking position and in which the unlocking of the car can only be performed simultaneously with or subsequent to the actual bodily removal of the key from its key hole or slot. I also find it highly advantageous, under some circumstances to have a lock in which the

forward movement of locking position of the bolt is performed manually by a plurality of different movements and against an appreciable resistance instead of tripping the locking bolt so that it would be shot forward by a heavy spring into locking position.

In the drawings:—

Figure 1 is a front elevation partly in section.

Figure 2 is a sectional view at right angles thereto and taken thru the centerline of the locking bolt.

Figure 3 is a side elevation.

Figure 4 is a top plan view.

Figure 5 is a horizontal section thru the axis of the trip.

Figure 6 is a fragmentary side elevation.

The housing consists of two sections 10 and 11 which snugly embrace the steering post casing 12, the larger portion 10 of the casing 70 having a boss 14 and the smaller portion or cap 11 having a similar boss 15, these bosses fitting circular holes in the steering post casing 12 and cooperating with the powerful frictional contact to hold the housing securely in place. The two parts of the housing are secured together on the top by means of special "one way" screws 17 which seat rather deeply in bores 18 which are subsequently filled with metal plugs or caps 19. The details so far mentioned are old in the art and are mentioned here merely for fullness of description. The locking bolt 20 slides radially of the steering post and engages in a hole thru one or more of the rotatable tubes, here shown however as entering only the steering post tube 21. The locking bolt slides in a cylindrical bearing in the boss 14 and also in a central bore of a hollow cylindrical member 23 which, for convenience of description, will be referred to as the "block".

This block has also a rather large bore 24 slidably receiving the head 25 of the locking bolt 20, but which bore is closed at the top by means of a plug 26 permanently secured 95 to the block in any manner as by the threads illustrated, and having on its free or outer face a cylindrical lug 28 snugly received in the bore of a follower 30. A spring 31 tends to hold the block 23 elevated as seen in Figures 100

1 and 2 and the spring 32 interposed between the plug 26 and the circular head 25 of the locking bolt 20 tends to hold the locking bolt downward, that is, into locking position. It will be noted that in all the figures the device is shown in locked position.

The ignition circuit is brought to the device thru wires 33 and 33', electrically connected to a pair of spaced spring terminals 34 which may be bridged by a metallic cup 35 insulated from but carried by the follower 30 which slides in the large bore 37 extending from the top of the housing to within a short distance of the boss 14. The follower 30 is also guided in its up and down movement by a small hollow cylindrical bearing 38 pinned to the housing as at 39. A spring 40 in the bore of the follower 30 and engaging the flat top face of the lug 28 tends to hold the follower elevated or in a direction to close the ignition circuit by bridging the terminals 34 with the cup contact 35.

If the parts so far described were free to move, the spring 31 would elevate the block 23, withdrawing the end of the locking bolt into the boss 14 and the spring 40, upon such movement of the block, would move the contact 35 to close the ignition circuit. A detent 43 sliding in a bore 44 in the housing or preferably, for convenience of manufacture, in a plug 45 pinned to the housing as at 46 is urged by a spring 47 toward the axis of the bore 37, the detent 43 having a lower yoke 48 overlying the top of the block 23 and having an upper yoke 49 overlying the skirt 50 of the follower 30 as best shown in Figure 2.

The detent 43 carries a pin 51 passing thru a slot 53 in a slabbed face of the plug 45 and lying in the path of an arm 55 fast on the end of the cylinder of a plunger type lock 56 so that when the lock is operated by the key (not shown) the arm 55 engages the pin 51, withdrawing the detent 43 to the right as seen in Figure 2, compressing the spring 47, and allowing the block 23 to shoot, under urge of the spring 31, to an upper or steering post unlocking and circuit closing position, in absence of mechanism illustrated but not so far described.

The shaft 60 passes entirely thru the housing from side to side having on one end a small washer 61 which serves to prevent movement of the shaft to the right as seen in Figure 1 and carrying centrally a one toothed pinion 62 keyed or splined to the shaft. A small spring pressed plunger 63 having a spool-type head 64 is slidably mounted in a bore 65 in the housing so that the stem or bolt-acting-end of the plunger may project into the large vertical bore 37. A spring 66 acting against the end of the larger bore 65 and against the head of the plunger 63 normally holds the plunger out of the bore 37 and holds a lever 68 fast on the other end of the shaft 60 in a position so that

the free end 69 of the lever covers the key hole slot 67 or opening of the lock 56.

A small stop pin 70 is fixed to the housing and the lever 68 is provided with an arcuate slot 71 limiting the angular movement of the lever and hence preventing the shooting of the plunger 63 out of its bore. While not necessary the pin 70 may also limit the inward movement of the plunger 63, which inward movement, however, is limited by engagement with the cylindrical wall 75 of the follower when the parts are in locked position, or is blocked by the cylindrical wall of the block 23 when the parts are in unlocked position.

Movement of the block 23 in an upward direction is taken care of by the spring 31 but movement downward, that is, into locking position, of this member, is preferably taken care of manually. To this end I secure to the block 23 a pin 77 which may be used as the means for securing the plug to the block as it passes diagonally thru both. The pin 77 extends entirely thru one side of the housing and projects beyond the face of the housing shown in elevation in Figure 6.

A handle 78 consisting of a disk 79 and a rod-like portion 80 integral therewith has a bore therein slidably receiving the pin 77 and having in the bore a spring 82 engaging the outer flat face of the pin so as to push the handle away from the end of the pin. In the housing I drive a disk shaped closure 85 which is pinned or otherwise secured in place, is flush with the outer face of the housing on its outer side and is recessed by a circular depression 87 and also by a still deeper recess 88 which recesses are so joined that the disk 79 may slide freely from the shallower to the deeper depression.

A slot 89 in the closure 85 permits up and down movement of the handle 80. In locked position the handle 78 engages the bottom of the slot 89 and the bottom of the shallower depression 87 and when the detent 43 is retracted to free the block 23 practically no resistance is given by the handle as it is free to fly upward except for the slight friction of the disk like collar 79 against the wall of the closure 85.

When the block 23 is in its uppermost position the smaller portion 80 of the handle is at the top of the slot 89 and the disk like collar 79 is positioned at or near the bottom of the deeper circular recess 88. A straight downward movement of the handle 80 is prevented by engagement of the disk 79 with the recess 88 but a direct inward push of the handle 78 compresses the spring and frees the disk 79 of such engagement and then allows the handle to move downward, such downward movement being resisted by the spring 31. The movement required and the resistance of the spring 31 make it quite impossible to move the part into locking posi-

tion accidentally and also prevent the locking of the device by means of a blow. Furthermore it is to be noted that unless the downward movement of the block 23 is entirely completed the spring 31 will restore the parts to unlocked position. It should furthermore be borne in mind that the ignition circuit is not broken until after such completion of the stroke for if the block were lowered almost to the bottom position and then restored, the ignition circuit would remain "on" for the entire time.

Referring again to the detent 43, it will be seen that the lower surface of the yoke 49 has a slight bevel and that the upper and outer peripheral surface of the circular skirt 50 is also slightly beveled. The function of these bevelings is to lower the follower 30 (thereby opening the ignition circuit) upon the shooting forward of the detent 43, which forward movement can only take place at the time the plunger 63 is withdrawn. The latter is projected forwardly and into position to prevent upward movement of the follower 30 by engagement with the skirt 50 as long as the key is in the key slot.

The operation of the device is as follows:— The car is locked and the owner desires to operate it. Since the parts are in locked position the only resistance to movement of the lever 68 is had by the spring 66 and this is quite slight. The owner thereupon presses down the free end 69 which throws the plunger 63 into position above the skirt 50. The key is now turned in its slot in the lock cylinder, engagement of the cam arm 55 withdrawing the trip 43 entirely within its bore 44, thus freeing the block 23 to move upwardly under the urge of its spring 31 into engagement with the bottom of the skirt 50.

Although not at all essential, I prefer that the locking bolt 20 be of such length as not to clear the steering post upon such upward movement. Nothing else happens until the key is removed; the key cannot be turned thru a complete revolution because of engagement of the pin 51 with the end of the slot 53, and must therefore be returned to initial position and withdrawn. Upon withdrawal of the key, the spring 66 withdraws the plunger, restoring the key lever 68 to key hole closing position, the spring 31 completes the upward movement of 23, and this, and the urge of the spring 40 throws the contact 35 into circuit closing position. This is the running position.

The owner now wishes to stop the car. He can only open the ignition by first locking the car. This he does by first an inward push of the handle 78 and then a downward movement of this same handle. As soon as the handle goes to the bottom of its stroke the heavy spring 47 shoots the detent 43 forward locking down the block 23 and camming

down the follower 30 by the upper yoke 49 engaging the sloping camming surface of the skirt 50. This is the locked position illustrated.

What I claim is:—

1. In a device of the character described, a bolt, means for moving the bolt to locking position, key controlled mechanism for withdrawing said bolt from locking position, and means barring entry of said key into its key-slot while the bolt is withdrawn. 70

2. In a device of the character described, a bolt, means for moving the bolt to locking position, key controlled mechanism for withdrawing said bolt from locking position, and 80 means barring withdrawal of said bolt while said key is in its key-slot.

3. In a device of the character described, a bolt, means for moving the bolt to locking position, key controlled mechanism for withdrawing said bolt from locking position, and means preventing withdrawal of said bolt until after said key is removed from said key controlled mechanism. 85

4. In a device of the character described, a spring retracted bolt, means for moving the bolt to locking position against said spring, means controlled by a rotatable cylinder key operated lock for withdrawing said bolt from locking position, and means barring entry 95 of the key into its key-slot while the bolt is withdrawn.

5. In a device of the character described, a bolt, means for moving the bolt from locking position to unlocked position and for 100 moving the bolt from unlocked position to locking position, a key operated mechanism controlling a portion of said means, and a member having two positions, in one of which the bolt is prevented from completing its movement in one direction and in the other position the key is barred from entry into its key hole. 105

6. In a device of the character described, a reciprocating bolt, a spring moving said bolt in one direction, key controlled mechanism for moving said bolt in the opposite direction and against said spring, a member having angular movement, and resilient means holding said member at one limit of 115 its travel in position to cover the key slot of said key controlled mechanism, and further means connected to said member and serving to interfere with the movement of the bolt when said member is moved from key slot 120 covering position. 125

7. In a device of the character described, an ignition circuit, a reciprocating follower adapted to move to close the ignition circuit, a member movable in one direction to lock the steering post against movement with respect to its casing and movable in the opposite direction to cause said follower to close the ignition circuit, means to move said member to locking position, and means to prevent 130

movement of the follower to circuit closing position upon movement of said member toward unlocking position.

8. In a coincidental lock, means for opening and closing the ignition circuit, a bolt movable to position to lock a movable member against movement with respect to the stationary parts of the automobile, a member movable to position to prevent the completion of the ignition closing movement, and resilient means for withdrawing said member to permit completion of the ignition circuit closing movement.

9. In a coincidental lock, an ignition circuit, a contact movable to open or close the circuit, a follower secured to said contact, means tending to move said follower to circuit closing position, a locking bolt, a member adapted to withdraw said bolt from locking position and to engage said follower to close the circuit, a detent preventing movement of said member in one direction, key controlled mechanism for withdrawing said detent, and means preventing withdrawal of said bolt as long as the key is in its slot in the detent withdrawing mechanism.

10. The device of claim 9 in which the last mentioned means includes a member slideable into position to prevent said follower from closing the ignition circuit.

11. The device of claim 9 in which movement of the last mentioned means upon withdrawal of the key, frees the follower to complete its circuit closing movement.

12. In a lock, a make and break device, a slide secured to the moving portion of said device, means for locking two members against relative movement, a detent for holding said means in locked position, and means on said detent for moving said slide to operate said make and break device.

13. In an electrical switch, a contact, a second contact movable into engagement therewith, to close a circuit, a spring urging said second contact to circuit closing position, a manually operated member engaging the free end of said spring and a device movable into position to limit movement of said member and simultaneously to withdraw said contact and open the circuit.

14. In a coincidental lock, a circuit make and break device, a follower secured to one member thereof, a sliding member, a locking bolt, a spring between said sliding member and said follower, a second spring between said sliding member and said bolt, resilient means for withdrawing said bolt from locking position, a detent for preventing such movement, means for withdrawing said detent, resilient means urging said detent to position to prevent withdrawal of the locking bolt, means carried by said detent for compressing the spring between the follower and the sliding member, and means for preventing movement of the follower under urge

of the spring between it and the sliding member during movement of the detent retracting means.

15. In an ignition control device, a fixed contact, a second contact adapted to move into engagement therewith to complete a circuit, a spring urging the movable contact into circuit closing position, a sliding member adapted to move said second contact into circuit opening position, key operated means for withdrawing said sliding member and an additional means for preventing movement of said second contact into circuit closing position until after removal of the key from said key operated means.

16. In a switch a member movable to open or close a circuit, a latch preventing movement of said member to circuit closing position, a second latch for holding said member from moving to circuit closing position, key operated mechanism for withdrawing said second latch, and means attached to said first latch blocking the key hole of said mechanism when said first mentioned latch is withdrawn.

17. In a circuit controlling device, a member movable to make or break a circuit, means to move said member in one direction, means to move said member in the other direction, means including a rotatable-cylinder key operated lock for moving one of said means, and means which must be thrown to position to block movement of said member when the key is in the lock and automatically releasing said member upon removal of the key from said lock.

18. In a circuit control, a member movable to make or break an electric circuit, a detent movable in one direction to move said member to one limit of its travel, key operated means for moving said detent to the other end of its travel to free said member, a block movable to withhold said detent in inoperative position, a spring pressed latch movable into position to prevent movement of said member, a spring urging said latch to inoperative position, and a lever operatively connected to said latch to move under the urge of said spring to a position to cover the key hole of the key operated means when the latch is withdrawn.

19. In a coincidental lock, a circuit closing member, a bolt, a detent to prevent contact between said member and bolt, a second detent to prevent movement of said circuit closing member, and means operatively connecting said detents so that one detent must be moved to barring position before the other detent can be freed.

20. In a lock, a spring operated bolt, detent means for holding the bolt in locking position, and independent means for preventing withdrawal of said bolt after the detent is moved to position to free the bolt.

21. The device of claim 20 in which the

detent means is key operated and the withdrawal preventing means is controlled by the presence of the key in the key operated detent mechanism.

5 22. The device of claim 20 in which the detent controls the making and breaking of an electric circuit.

10 23. The device of claim 20 in which the detent is operated by a key and the removal of the key from its key slot automatically frees the bolt from the withdrawal preventing means.

15 24. The device of claim 20 in which the detent controls the making and breaking of an electric circuit and is key operated, the withdrawal of the key from its key slot releasing the withdrawal preventing means to allow said means to move to position to free the bolt.

20 25. The device of claim 20 in which the bolt is spring retracted and the detent in its movement controls the making and breaking of an electric circuit.

25 26. The combination with a coincidental lock of the type in which the locking of the car breaks the ignition circuit and the unlocking of the car closes the ignition circuit, of means for delaying the unlocking of the car until after the lock operating means is withdrawn from the lock.

30 27. The combination with a coincidental lock of the type in which the locking of the car breaks the ignition circuit and the unlocking of the car closes the ignition circuit, of means for delaying the closing of the ignition circuit until after the lock operating means is withdrawn from the lock.

35 28. The combination with a coincidental lock of the type in which the locking of the car breaks the ignition circuit and the unlocking of the car closes the ignition circuit, of means for delaying the unlocking of the car and the closing of the ignition circuit until after the lock operating means is withdrawn from the lock.

40 29. In a steering post lock, a bolt, an ignition circuit switch contact, a sliding member, a spring to urge the sliding member in one direction, a spring to urge the bolt in the opposite direction, and a third spring urging the contact away from the sliding member.

45 30. In a lock, a hollow sliding member, a bolt slidable in said member, opposed resilient means urging the bolt in opposite directions, an ignition switch plunger, means urging the plunger from the sliding member and into ignition circuit closing position, and key operated means for holding the plunger out of ignition circuit closing position.

50 31. In a lock, three coaxial members one a locking bolt, three spaced springs each engaging one of said members, and a detent

engaging simultaneously two of said members.

55 32. In a coincidental lock, three coaxial members, one a locking bolt, one an ignition circuit switch carrying follower, and the other a spring pressed plunger, a spring between the bolt and the plunger, a spring between the follower and the plunger, and detent means engaging the plunger and the follower to hold the plunger in spring compressed position and to hold the follower in ignition circuit open position.

60 In testimony whereof I affix my signature.

CHARLES N. FAIRCHILD.
